WRITING INSTRUMENT

Rosario J. Rizzo, Elmont, N. Y., assignor to Ferber Corporation, Bergen County, N. J., a corporation of New Jersey

Application February 28, 1955, Serial No. 490,739

5 Claims. (Cl. 120—42.03)

This invention relates to writing instruments and more particularly to those wherein the writing point is extended and retracted from its writing position by the operation of a push button.

It is an object of the present invention to provide a writing instrument having a writing cartridge and point which may be positively propelled from the instrument and retracted thereinto by the operation of a novel push button device.

Another object of the invention is to provide a writing instrument wherein the writing cartridge is movable to a first position in which the same is positively held extended from said instrument for writing and to a second position in which it is positively held withdrawn into the instrument.

A further object of the invention is to provide a push button mechanism including novel means for positively positioning and writing cartridge in either the first or second positions. To this extent a feature of the invention resides in the unique operation of the novel cartridge positioning means.

Other and further objects of my invention reside in the structures and arrangements hereinafter more fully described with reference to the accompanying drawings in which:

Fig. 1 is a sectional elevational view of the writing instrument constructed in accordance with the principles of the invention and with the cartridge and writing point withdrawn into the instrument.

Fig. 2 is a view similar to Fig. 1 with the cartridge and writing point being positioned in their extended position by the operation of the push button.

Fig. 3 is a partial view similar to Fig. 2 wherein the cartridge and writing point are held extended and the push button is in its normal inoperative position.

Fig. 4 is a partial side elevation of Fig. 1 taken along lines 4—4.

Fig. 5 is a sectional view of Fig. 1 taken along lines 5—5.

Fig. 6 is a sectional view of Fig. 1 taken along lines 6—6, and

Fig. 7 is a view of a modified push button.

Referring now to the drawings, the writing instrument 10 comprises a lower sleeve 12 and an axially contiguous upper sleeve 14. The sleeves 12 and 14 are threadedly secured together at 16 and a cover 18 extends about the upper sleeve 14 and is secured to the lower sleeve 12 at its lower end in an undercut 20 (see Figs. 1 and 2).

The upper sleeve 14 has a bifurcated upper end portion defining the bifurcations 22 and 24. The space or slot (not numbered) defined between the bifurcations 22 and 24 has a definite function which will become obvious as the description proceeds. Defined axially in and centrally of the sleeve 14 and at the upper ends of the bifurcations 22 and 24 is a substantially oval-shaped opening 26. Axially below the oval-shaped opening 26 the sleeve 14 has an enlarged hollow interior 28 also substantially oval-shaped and better seen in Fig. 6. Included

2

in the interior 28 is a laterally offset circular guide opening 29 (Figs. 1, 2, 3 and 6) having at its top the first of two abutments or shoulders 30 and 32.

The shoulders 30 and 32 are each laterally offset on opposite sides of the center of the sleeve 14 and axially spaced from each other within the interior 28. The shoulder 30 is positioned at the top of the offset guide opening 29 and axially higher than the shoulder 32 which has a hook edge 33 (Figs. 1, 3 and 6). Each of the shoulders 30 and 32 cooperates with an axially extendable and retractable cartridge 34 having a writing point 36. In Fig. 1 the cartridge 34 is shown retracted within the writing instrument 10 and with the writing point 36 thereof withdrawn into the body of the lower sleeve 12. In Fig. 2 the same cartridge 34 is shown in its propelled or extended position with the point 36 thereof axially beyond the end of the lower sleeve 12. When the cartridge 34 is moved to either one of the two aforementioned positions by a structure to be described it is positively retained in such positions by the cooperation of a flared edge 38 at the upper portion of the cartridge which forms a catch adapted to engage the shoulder 30 or 32 respectively.

The writing cartridge 34 is moved to and from its writing position by a novel push-button structure at the top 25 of the instrument 10, generally identified by the numeral 40. The structure 40 comprises a finger-operated button 42 which extends beyond the top of the instrument 10 through an opening (not numbered) in the cover 18. The button 42, bifurcated at its lower portion, has a substantially oval-shaped outer periphery slightly smaller than the oval opening 26 in the sleeve 14 to guidingly admit the button 42 therein. The cooperating oval opening 26 and the oval shape of the button 42 allow axial relative movements between the button and sleeve 14, but at the same time eliminate any tendency of relative rotation therebetween.

In a slot 44 defined between the bifurcations of the button 42 there is positioned a laterally pivotable tongue 46 having a shoulder 48 thereon. When the tongue 46 is 40 positioned between the bifurcations of the button 42, the laterally spaced shoulders 48 thereof are axially aligned in height with a peripheral shoulder 50 (see Figs. 2 and 4) of the button 42. The tongue shown in the embodiment in Figs. 1 to 6 has cast integral therewith, and on opposite sides thereof, trunnions 52 at the same level with shoulders 50. Said trunnions 52 ride in opposed, but facing axial grooves 54 in the inner faces of the bifurcations of the button 42. The grooves 54 are best seen in Fig. 4. Although the trunnions 52 are freely and axially 45 slideable in the grooves 54, the tongue 46 is retained centrally in position in the slot 44 of the button 42 by a light spring 56 which is seated on a peripheral upper shoulder 58 of the sleeve 14 at its one end and against the shoulders 48 and 50 of the tongue and button respectively. Hence, the light spring 56 constantly retains the tongue 46 within the slot 44 of the button 42 and urges the button 42 into its extended position as is shown in Figs. 1 and 4.

From the drawings it will be noted that the pivot, namely the trunnions 52, of the tongue 46 is positioned centrally of the button 42, and at the same time is permitted lateral movement relative to the button 42 by way of the slot 44 and also the slot in the sleeve 14. The manner and purpose of the lateral pivotal movement of the tongue will become obvious as the description proceeds. However, along the lower surface of the tongue there is provided a cartridge-engaging means in the form of shoulder-defining notches 60 and 62, each of which is laterally offset on opposite sides of the center of the button 42. At the lower portion of the cartridge 34 there is provided a 55 detent means 64 which serves as a shoulder for one end of a spring 66, while the other end of the spring bears against a shoulder 68 at the lower portion of the sleeve

12. The spring 66 is substantially stronger than the upper spring 56 to apply a constant urging but yielding force on the cartridge 34 to urge the cartridge into engagement with either one of the two shoulders 30 and 32.

Under normal conditions and when the instrument is not in use the cartridge 34 will be retracted into the body of the instrument and the point 36 withdrawn within the confines of the sleeve 12. The flared part 38 of the cartridge 34 will be positioned in the opening 29 and in abutment with the axially upper and laterally offset shoulder 30 and yieldingly retained thereagainst by the relatively strong spring 66 acting upon the lower end thereof. The push-button actuating structure 40 will be yieldingly extended beyond the upper end of the instrument by the spring 56 acting thereupon.

To propel the writing point 36 beyond the lower end of the sleeve 12, the button 42 is manually depressed against the pressure of the spring 56. The bifurcated oval portion of the button will slide axially in and be guided by the mating oval opening 26 in the sleeve 14 with the tongue 46 depending downwardly and yieldingly held centrally of the button by the spring 56. Continued manual depression of the button brings the offset cartridge-engaging notch 60 into alignment with the flared edge 38 and subsequently into cooperating engagement therewith. Further downward pressure exerted on the button 42 overcomes the relatively stronger lower spring 66 to move the cartridge 34 down along the walls of the offset, slightly larger guiding opening 29 until the flare 38 passes axially below the walls of the opening and the hook edge 33 of shoulder 32.

Because the point of engagement between the cartridge flare 38 and the notch 60 of the tongue 46 are offset to the right of the center of the button 42 and the pivot 52, forces exerted on the tongue by the cartridge are directed laterally to cause the tongue to pivot laterally in the enlarged opening 28 until the cartridge is moved against the opposite wall of the opening and positioned directly under the shoulder 32. Continued downward depression of the button 42 is halted by the touching of a shoulder 51 (Figs. 1, 2 and 3) on the button 42 with the top of the sleeve 14. When the button is released the cartridge 34 is urged into secure engagement with the shoulder 32 by the combination of the spring 66 and the hook edge 33 (see Fig. 3).

To remove the cartridge 34 from its extended writing position it is necessary to disengage the flared portion 38 thereof from the axially lower shoulder 32 and place the same in engagement with the upper shoulder 30. Quite obviously the button 42 will be in its extended position beyond the head of instrument 10 while the tongue 46 is yieldingly retained in its depending position centrally of the button. Depressing the button 42 brings the notch 62 of the tongue 46 in alignment with the free portion of the flare 38, viz., the portion which is free from engagement with the shoulder 32. Continued downward movement of the button 42 engages the notch 62 with the flare 38 to move the cartridge 34 axially and still further beyond the end of the sleeve 12. The axial movement of the button structure 40 and the cartridge is halted by the touching of the shoulder 51 with the sleeve 14.

In the meanwhile, as soon as the flared portion 38 is moved axially below the hook 33 the tongue is caused to pivot in the slot 44 of the button 42 and in the coextensive slot in the sleeve 14 by lateral forces exerted thereon by the cartridge 34 and its spring 66. These forces, being due to the offset of notch 62 to the left of the center of button 42 and the pivot 52 (Figs. 1, 2 and 3), exert a lateral thrust on the tongue 46 causing the same to pivot the cartridge away from beneath the shoulder 32 and into alignment with the opening 29 and the shoulder 30. When the button 42 is released the cartridge is urged into secure engagement with the shoulder 30 by the spring 66 and the actuating structure

40 is returned to its normal extended position by the spring 56 which simultaneously restores the tongue 46 to a central position.

Fig. 7 shows a modified embodiment of the actuating push-button structure disclosed in Figs. 1 to 6 and is identified by the numeral 140. The actuating push-button structure 140 is almost exactly the same as that previously described except, however, that the pivot pin 152 replaces the ball-shaped trunnions 52 on the tongue 46 and the cooperating grooves 54 on the button 42. It will be noted that the pin 152 extends between the bifurcations of the button 142 and the tongue 146 is freely pivotable in the slot 144. It will be clear that the instant modified structure 140 operates in exactly the same manner as the previously described button structure 40.

While there have been shown and described and pointed out the fundamental novel features of the invention as applied to several preferred embodiments thereof, it will be understood that various omissions and substitutions and changes in the form and details of the devices illustrated and in their operations may be made by those skilled in the art, without departing from the spirit of the invention. It is the intention, therefore, to be limited only as indicated by the scope of the claims appended hereto.

Although the part 38 has been described as flared such construction is not controlling since it is within the contemplation of the invention that the shoulder-engaging catch portion 38 of the cartridge 34 need not be flared at all.

What I claim is:

1. In a writing instrument, in combination, a bifurcated button having a substantially oval-shaped periphery, a bifurcated sleeve having a substantially oval-shaped opening axially thereof and slidably receiving the furcations of said button longitudinally thereof, said sleeve having an enlarged hollow interior having defined therein two axially spaced shoulders each laterally offset from and on either side of the center thereof, a cartridge movable axially and laterally in said enlarged interior and engageable alternately with said respective shoulders, and a tongue pivoted to said button between the furcations thereof and swingable between the furcations of said sleeve, said tongue being formed with two shoulders each laterally offset from and on either side of the pivotal axis of said tongue to alternately engage with said cartridge upon sliding movement of said button to effect lateral shifting of said cartridge into engagement with respective shoulders.

2. The combination according to claim 1, wherein said button has facing grooves in facing surfaces of the furcations thereof, said tongue having trunnions cast integral therewith to cooperate with said facing grooves to provide a pivot mounting for said tongue on said button.

3. The combination according to claim 1, wherein said pivot includes a pin in said button, extending between the furcations thereof, on which said tongue is mounted.

4. In a writing instrument, in combination, an elongated sleeve provided at opposite ends with a first and a second opening communicating with its interior, a cartridge axially movable in said interior between an extended and a retracted position, said cartridge having a writing point projecting from said first opening in said extended position, resilient means urging said cartridge into said retracted position, a button non-rotatably held in said second opening for axial displacement relative to said sleeve, and a tongue pivoted to said button, said sleeve being provided in its interior with two axially spaced shoulders on opposite sides of said tongue, said cartridge terminating opposite said writing point in a catch laterally displaceable for engagement with either of said shoulders whereby said cartridge occupies either said extended or said retracted position, said tongue having formations laterally offset from its pivot on either side thereof and alternately engageable with said catch, upon inward dis-

placement of said button against the action of said resilient means, whereby engagement of a formation on one side of the pivot to exert a force on said catch for movement away from said pivot effecting dislodgement of said catch from the shoulder engaged thereby, said tongue and said resilient means being jointly effective to move said catch sideways toward the other shoulder for engagement therewith upon subsequent release of said button.

5. The combination according to claim 4, wherein said button is bifurcated, said tongue being pivoted to said 10 button between the furcations thereof.
